INVENTOR:

Paul Jaray

UNITED STATES PATENT OFFICE.

PAUL JARAY, OF FRIEDRICHSHAFEN, GERMANY, ASSIGNOR TO THE FIRM LUFT-SCHIFFBAU ZEPPELIN GESELLSCHAFT MIT BESCHRÄNKTER HAFTUNG, OF FRIEDRICHSHAFEN, GERMANY.

REVERSIBLE AIR PROPELLER.

Application filed June 28, 1920. Serial No. 392,572.

To all whom it may concern:

Be it known that I, PAUL JARAY, a citizen of the Austrian Republic, residing at Friedrichshafen a/B., Germany, have invented certain new and useful Improvements in Reversible Air Propellers, of which the following is a specification.

My invention refers to propellers for aerial vehicles and its particular object is to provide means for reversing the propeller in a simple and yet effective manner, the efficiency of the propeller being the same before and after reversal.

As is well known to those skilled in the art, it is necessary to reverse the propeller i. e. to make it act in an opposite direction whenever an airship or a flying machine is about to land inasmuch as these vehicles, provided that the propeller be merely brought to a standstill, will, owing to their own momentum and the low resistances encountered, persist for a while in their forward movement.

Now by merely changing the direction of rotation of the propeller shaft the effective output of the propeller, which latter is now rotating backwards, becomes very low inasmuch as the suction side is then required to act as pressure side and vice versa. It is not possible either to improve this low efficiency by employing propellers having adjustable blades allowing to be gradually set between comparatively low angular limits. For small gradual angular variations of this kind will prove useful only in case that the direction of travel remains substantially the same, provided the density of the air, the gradient and the velocity, respectively, be varied therewith.

In the propeller according to the present invention, now, instead of gradually setting the propeller blades, provision is made that the front and rear faces of the blades together with the inlet and outlet edges will assume their correct positions even after the direction of rotation has changed. This is effected by reversing in a well known manner the propeller shaft and at the same time also causing the blades to turn about 180° around their longitudinal axis until they have reached the opposite position. Thus the propeller according to the present invention is provided with means for adjusting its blades in two ter-

55 minal positions, each one, provided that the propeller shaft be caused to rotate in a corresponding sense, resulting in the correct position of the inlet and outlet edges for going ahead and astern, respectively.

In the drawings affixed to this specification and forming part thereof the preferred form of a reversible propeller is illustrated by way of example. In the drawings—

10 Figs. 1 and 2 are a longitudinal and a cross section, respectively, of the central portion of the propeller and hub.

15 A is the propeller shaft and B is a hub casing affixed thereto. C is a bush rotatably disposed within said hub and embracing the propeller D which is secured thereto against rotation by lateral faces d^1 and screw bolts E. Shoulders b^1 on the bush C prevent this latter from being displaced in an axial direction. C¹ is a worm rim formed on the bush C and G is a worm disposed on 70 a shaft located in the hub and carrying a chain wheel F.

20 Whenever it is desired to reverse the propeller, the propeller shaft is caused to rotate in an opposite direction. At the same time chain wheel F is caused to rotate from a distance and the bush C and propeller D are thereby carried into the opposite position where the inlet and outlet edges again assume their correct position with relation 75 to the changed directions of rotation, the propeller thereby working with full efficiency.

25 Although I have represented the propeller as being made in one piece, as usual, I 80 wish it to be understood that my invention may just as well be applied to propellers having separate blades jointed together by means of a common hub. In such a case the reversing mechanism will again be connected with the hub. As the propeller is reversed for full 180° , there is no hindrance to its blades being rigidly interconnected by the hub inasmuch as in contradistinction to a setting for a smaller angle the direction 85 of turning has no influence upon the propeller action.

30 The invention may further be applied with equal advantage to propellers provided with more than two blades.

I claim:

35 1. In combination, a propeller comprising two blades rigidly connected in relation

to each other, a propeller shaft, a hub casing fixed to said shaft, a bush embracing the middle portion of said propeller, means for rigidly securing said propeller in relation to said bush, a bearing in said hub casing for rotatably supporting said bush together with said propeller, and means for turning said bush together with said propeller 180 degrees around their common longitudinal axis.

2. In combination, a propeller comprising two blades rigidly connected in relation to each other, a propeller shaft, a hub casing fixed to said shaft, a bush embracing the

middle portion of said propeller, means for rigidly securing said propeller in relation to said bush, a bearing in said hub casing for rotatably supporting said bush together with said propeller, a worm rim on said bush, a worm mounted in said hub casing and engaging with said worm rim, and means for operating said worm adapted for turning said bush together with said propeller 180 degrees around their common longitudinal axis.

In testimony whereof I affix my signature.

PAUL JARAY.
